UNITED STATES PATENT OFFICE.

CHARLES N. HUNTER, OF VERSAILLES, INDIANA.

THILL-COUPING.

SPECIFICATION forming part of Letters Patent No. 615,990, dated December 13, 1898.

Application filed February 19, 1898. Serial No. 670,923. (No model.)

To all whom it may concern:

Be it known that I, CHARLES N. HUNTER, a citizen of the United States, residing at Versailles, in the county of Ripley and State of Indiana, have invented new and useful Improvements in Thill-Couplings, of which the following is a specification.

My invention relates to thill couplings and supports, and its novelty and advantages will be fully understood from the following description and claims when taken in conjunction with the annexed drawings, in which—

Figure 1 is a plan view of a pair of thills connected to an axle by my improved couplings and equipped with my improved supports. Figs. 2 and 3 are enlarged detail sections taken in the planes indicated by the lines $\alpha\alpha$ and yy , respectively, of Fig. 1. Fig. 4 comprises disconnected perspective views of parts of one coupling, and Fig. 5 is a detail perspective view of one clip-plate.

Referring by letter to the said drawings, A designates the axle of a vehicle, B designates a pair of thills, and C designates the couplings for connecting the thills to the axle. These couplings are similar in construction, and therefore a description of the one shown in detail in Figs. 2 and 4 will suffice for both. Said coupling comprises the thill-iron a , having the enlargement b , the clip c , arranged on the axle and having the lugs e , provided with the transverse apertures f , and also provided in their inner sides with grooves g , arranged coincident with and extending upwardly from the apertures f , the clip-plate d , secured to the clip, and the bolt h , arranged in the apertures f of the lug and having the elongated diametrically-disposed slot i , as shown. The enlargement b of the thill-iron a corresponds in length to the distance between the outer walls of the grooves g of lugs e , as does also the slot i in bolt h . In virtue of this it will be seen that when the slot i of bolt h is coincident with the grooves g of lugs e the enlargement b of the thill-iron a may be readily introduced to or removed from its position in the slot of the bolt. Such introduction and removal of the thill-iron can only be effected when the thill is in an upright position, for when it is in a horizontal or approximately horizontal position the enlargement b will be disposed at an angle to the grooves g , as

shown in Fig. 1. It follows from this that while the thills may be quickly and easily disconnected from the axle when said thills are in an upright position there is absolutely no liability of said thills being casually disconnected when in their operative position—*i.e.*, horizontal or approximately horizontal—which is a desideratum.

D designates the improved thill-supports, which have for their purpose to yieldingly support the thills in the operative position desired and are designed with a view of permitting the thills to be readily connected to and disconnected from the axle in the manner before described. The said supports D are similar in construction and they respectively comprise a clip j , arranged on the axle, a plate k , connected to the ends of said clip and having the downwardly and forwardly pitched and slotted arm l , the rod m , which is fixedly connected to the lateral branch n and the main portion of the thill-iron a and rests loosely in the slot of arm l and is threaded at an intermediate point of its length, as indicated by p , the nut q , which is mounted on said threaded portion p of the rod, and the coiled spring r , which surrounds the rod and is interposed between the nut and the arm l of the clip-plate k , as shown. The coiled springs r of the supports D are sufficiently strong to support the thills in their operative position and take the weight of the same off the draft-animal. The said springs are also designed and adapted to support the thills in their operative or horizontal position when the draft-animal is removed. In virtue of the construction of the supports it will also be observed that they may be readily adjusted, so as to support the thills at various heights and adapt the same to horses of various sizes. In effecting such adjustment when the thills are too low the nut q is turned down upon the rod m , so as to contract the spring r and raise the thills, while when said thills are too high the nut is moved away from the lower end of the rod, so as to permit the spring to expand and the thills to move downwardly.

While the supports D are adapted to be adjusted in the manner described, they do not interfere with the thills being raised to a vertical position; nor do they interfere with the

thills being disconnected from the axle when they are in such position. When the thills are swung upwardly, the rods of the supports D are free to play in the elongated slots 5 of the arms l. Also when the thills are in a vertical position the supports D may be readily withdrawn from the slots of the arms l, while when the said thills are lowered the rods will reenter the slots of the arms l and 10 the springs will bear against said arms for the purpose described.

It is obvious that when desired my improvements may be employed in conjunction with the tongue or pole of a vehicle as well as with 15 thills.

Having thus described my invention, what I claim is—

1. The combination of an axle, a thill or pole provided with an iron, a clip fixed on 20 the axle, a pivotal connection between the thill or pole iron and the clip arranged to coact with means on said iron and clip to prevent disconnection of the thill or pole except when the same is in a vertical or approxi- 25 mately vertical position, the plate k connected to the axle and having the forwardly-extending arm l provided with an elongated slot, the rod permanently connected to the thill or pole and arranged to extend loosely through 30 the slot in arm l, when the thill or pole is in its operative position and having the threaded portion p, the nut mounted on said threaded

portion of the rod, and the coiled spring surrounding the rod and interposed between the nut thereon and the arm l, substantially as 35 and for the purpose set forth.

2. The combination of an axle, thills connected together by a cross-bar and provided with irons, clips fixed on the axle, pivotal connections between the thill-irons and the 40 clips arranged to coact with means on said irons and clips to prevent disconnection of the thills except when the same are in a vertical or approximately vertical position, plates 45 k connected to the axle at points between the clips and having the forwardly-extending arms l provided with elongated slots, the rods permanently connected to the thills and the cross-bar between the same and arranged to extend loosely through the slots in the arms 50 l when the thills are in their operative position and having the threaded portions p, the nuts mounted on said threaded portions of the rods, and the coiled springs surrounding the rods and interposed between the nuts 55 thereon and the arms l, substantially as and for the purpose set forth.

In testimony whereof I have hereunto set my hand in presence of two subscribing witnesses.

CHARLES N. HUNTER.
